UNITED STATES PATENT OFFICE.

LAWRENCE P. LEONARD, OF ST. CLOUD, MINNESOTA.

FRESH-AIR-TREATMENT APPARATUS.

No. 916,567.

Specification of Letters Patent. Patented March 30, 1909.

Application filed May 26, 1908. Serial No. 435,071.

To all whom it may concern:

Be it known that I, LAWRENCE P. LEONARD, a citizen of the United States, residing at St. Cloud, in the county of Stearns and 5 State of Minnesota, have invented certain new and useful Improvements in Fresh-Air-Treatment Apparatus, of which the following is a specification.

My invention relates to devices for treating 10 patients suffering from tuberculosis, pneumonia, anemia, etc., with fresh air.

On Feb. 18, 1908, there was granted to me United States Letters Patent No. 879,391, for day treatment of patients with fresh air 15 in which only the patient's nose was covered by the end of the inhaler but he was required to lie in one position to keep the device in place.

The invention hereinafter described and 20 claimed is particularly designed for use in treating patients at night and is constructed to inclose the patient's head so that the patient can turn in his sleep and still receive the benefits of the treatment.

25 The construction and operation of my improved apparatus for fresh air treatment is described hereinafter and illustrated in the accompanying drawings in which—

Figure 1 is a view showing the interior of 30 a room and the patient lying in bed with my improved apparatus in position, Fig. 2, a cross-section of the joint by which the induction tube is secured to the window, Fig. 3, a front view, on an enlarged scale, of the 35 diffusing chamber, Fig. 4, a side view, Fig. 5, a longitudinal sectional view thereof, and Fig. 6, a view showing an attachment for sliding windows.

In the drawings similar reference characters 40 indicate corresponding parts in all the views.

In the form shown in Fig. 1 my device is 45 shown in connection with a window A having a sliding sash B and a swinging storm sash B' controlled by means of a latch C. The device may be attached to the sliding sash B, or if desired a separate sash D may be used as shown in Fig. 6 and inserted under the lower sliding sash B or above the 50 upper sash as desired, the position of sash D being fixed by the height of the window sill from the floor. Where the window is not conveniently placed for attachment of my device it will be apparent that a hole

may be made in the outer wall of the building to accommodate the end of the induction tube and filter, hereinafter described, it not being considered to be necessary to illustrate this construction.

Secured to sash B or D is a plate 1 having a hole 2 therein opening to the outer air and with a socket 3 surrounding the hole to receive the spherical enlargement 4 on the end of induction tube 5.

6 indicates another plate having a hole 65 7 therein to receive tube 5 and upset around said hole as shown at 8 to form a socket to fit the spherical enlargement 4.

9 indicates bolts secured to plate 1 having eye-loops 9^a, and 10 hooked rods mounted 70 on plate 6 to engage said eye-loops 9^a, the ends of said rods 10 being threaded to receive wing nuts 11. This construction forms a ball and socket joint for the receiving end of induction tube 5 so that the tube may 75 be adjusted within certain limits to suit the position of the patient.

12 indicates a hook secured to the casing of the window A or other convenient place and 13 a spring secured to the hook and to 80 tube 5 to support it and still permit movement of the tube to accommodate itself to the movements of the patient.

The diffusing chamber consists of a cylindrical shaped casing 14 made of a heavy 85 air-proof fabric such as canvas and is secured to the inner end of tube 5 by means of a strap 15 run through guides 16 on the upper end of casing 14. The casing 14 is made preferably larger in diameter intermediate of its ends as shown at 17 and has 90 a hoop 18 secured at the large portion 17 and other hoops 19 between the upper end of casing 14 and the enlarged portion 17 so as to hold the upper portion of the casing 95 distended.

20 indicates bands of elastic material secured longitudinally of the casing between its upper end and enlarged portion 17 and adapted to normally pucker the upper end 100 of the casing so as to prevent it from sagging when not fully extended by the position of the patient. A hoop 21 is also secured to the lower edge of casing 14 to hold it distended.

22 indicates a hood secured to the lower edge of casing 14 by means of lacing strings, buttons or other detachable fastenings 22^a,

said hood being made of a softer fabric than that of said casing, is opened at the front as shown at 23 to receive the head of the patient, and has flaps 24 with any temporary 5 fastening means such as button holes and buttons to fasten them across the patient's throat. To protect the top of the patient's head from the air the hood 22 is continued inside of the casing as shown at 25 to engage 10 the forehead of the patient.

26 indicates pockets on the inside of the casing 14 to hold resinous material or other medicinal substance with which it may be desired to impregnate the air. 15 27 indicates a window of sheet celluloid or other transparent material to permit the patient to see what is going on around him and 28 an opening containing a gusset 29 and closed by a draw-string 30 engaging 20 button 31 or other fastening means to permit the patient to insert his hand and a handkerchief to reach his mouth and nose. 32 indicates a damper in tube 5 controlled by rods or other means 33 to regulate the ingress of air, said rods 32 being arranged conveniently to the patient as shown in Fig. 1.

The induction tube 5 may be made of any suitable material but I prefer to use wood 30 fiber, which is a nonconductor of heat, so as to prevent chilling the room.

In order that the air may be cleared of insects, dust, and other small particles floating therein before entering the induction tube 5 I secure a filter over the mouth of the tube consisting of a strip of wire mesh screen 34 covered by a layer of filtering cloth 35 such as mull or silk. In the drawings I have shown the filter secured by 40 means of bolts 9 to the outside of plate 1 but any other method of securing it in position may be substituted if desired.

Having thus described my invention what I claim is—

45 1. In a fresh air treatment apparatus, in combination with the window, a perforated plate secured thereto having a socket, the induction tube made of rigid material and having a spherical enlargement on its end 50 to engage said socket, and means to secure said enlargement in the socket.

2. In a fresh air treatment apparatus, in combination with the window, a perforated plate secured thereto having a socket, the induction tube made of rigid material and having a spherical enlargement on its end to engage 55 said socket, and another perforated plate formed with a socket to engage said enlargement and adjustably secured to the 60 first-mentioned plate.

3. In a fresh air treatment apparatus, in combination with the window, a plate secured thereto having a socket, the induction tube having a spherical enlargement 65 on its end to engage said socket, another

plate formed with a socket to engage said enlargement, hooked rods secured to one plate, and rods having eye-loops to engage said hooked rods secured to the other plate.

4. In a fresh air treatment apparatus, an 70 induction tube, a diffusion chamber secured to the inner end of the induction tube comprising a cylindrical casing of air-proof material, and a hood secured to the lower end of the casing.

5. In a fresh air treatment apparatus, an induction tube, a diffusion chamber secured to the inner end of the induction tube comprising a cylindrical casing of air-proof material formed to inclose a patient's head, 80 and hoops secured to said casing to hold it distended.

6. In a fresh air treatment apparatus, an induction tube, a diffusion chamber secured to the inner end of the induction tube 85 comprising a cylindrical casing of air-proof material formed to inclose a patient's head, hoops secured to said casing to hold it distended, and elastic bands secured longitudinally of the casing.

7. In a fresh air treatment apparatus, an induction tube, a diffusion chamber secured to the inner end of the induction tube comprising a cylindrical casing of air-proof material formed to inclose a patient's head, 90 and pockets on the inside of the casing to hold a medicinal substance.

8. In a fresh air treatment apparatus, an induction tube, a diffusion chamber secured to the inner end of the induction tube 100 comprising a cylindrical casing of air-proof fabric, an opening in said casing, and means to temporarily close said opening.

9. A fresh air treatment apparatus comprising in combination with a window or 105 other opening in the wall of a room, an induction tube secured in said opening by means of a ball and socket joint, a diffusion chamber secured to the inner end of said induction tube comprising a cylindrical casing of air-proof fabric, hoops secured to said casing to hold it distended, elastic bands secured longitudinally of the casing, a hood secured to the lower end of the casing and adapted to receive a patient's head 110 and neck, an opening above the hood, a gusset secured in said opening, a draw-string to close said opening, pockets on the inside of the casing to hold medicinal substances, and a transparent panel in the front 115 of the casing.

10. A fresh air treatment apparatus comprising in combination with a window or other opening in the wall of a room, an induction tube secured in said opening by 125 means of a ball and socket joint, a filter in the mouth of said induction tube, a diffusion chamber secured to the inner end of said induction tube comprising a cylindrical casing of air-proof fabric, hoops secured to 130

said casing to hold it distended, elastic bands secured longitudinally of the casing, a hood secured to the lower end of the casing and adapted to receive a patient's head and neck, an opening above the hood, a gusset secured in said opening, a draw-string to close said opening, pockets on the inside of the casing to hold medicinal sub-

stances, and a transparent panel in the front of the casing.

In testimony whereof I hereto affix my signature in the presence of two witnesses.

LAWRENCE P. LEONARD.
